UNITED STATES PATENT OFFICE.

MORTON L. BYERS AND THEODORE SHAVER, OF LOGANSPORT, INDIANA.

SWITCH AND SIGNAL MECHANISM.

SPECIFICATION forming part of Letters Patent No. 673,379, dated May 7, 1901.

Application filed December 4, 1900. Serial No. 38,604. (No model.)

To all whom it may concern:

Be it known that we, MORTON L. BYERS and THEODORE SHAVER, residents of Logansport, in the county of Cass and State of Indiana, have invented certain new and useful Improvements in Switch and Signal Mechanism, of which the following is a specification.

This invention provides improved means for operating and interlocking switch and signal apparatus. It is adapted for interlocking a distant signal with the switch. This is important where a switch is so situated that it cannot be seen from an approaching train in time to stop if found open when it becomes necessary to place an advance signal at sufficient distance from the switch to give ample notice of its position. For safety it is desirable to use such a mechanism that before the switch can be moved at all from the closed position the distant signal must be placed at "danger" and secured in that position by the slightest movement in opening the switch. It is also adapted for use as a "facing-point lock." In an interlocking plant it is frequently necessary to throw a switch by means of a pipe-line operated from a tower or distant point from which there are no means for determining whether the switch has actually moved to exactly its required position. Here a second mechanism is desirable for determining that the switch has operated properly and also for locking the switch when thrown to insure greater safety. It is adapted, further, for effecting the switch and lock movement or for performing by a single lever the operations of unlocking the switch, throwing the switch to a new position, and locking the switch in the new position.

The nature and further purposes of our improvements will more fully appear from the following detail description, taken in connection with the accompanying drawings, in illustration thereof.

In the accompanying drawings, Figure 1 is a diagrammatic view of the mechanism connecting a signal set at "proceed" and the closed switch. Fig. 2 is a diagrammatic view of a signal set at "danger" prior to opening the switch. Fig. 3 is a diagrammatic view of the signal held at "danger" with the switch open. Fig. 4 is a vertical sectional view of the interlocking mechanism, taken on the line

4 4 of Fig. 5. Fig. 5 is a horizontal sectional view of the interlocking mechanism, taken on the line 5 5 of Fig. 4. Fig. 6 is a perspective view of the interlocking disks. Fig. 7 is a side elevation of the interlocking disks in the relation corresponding to the position of the signal and switch illustrated in Fig. 1. Fig. 8 is a side elevation of the interlocking disks in the relation corresponding to the position of the signal and switch illustrated in Fig. 2. Fig. 9 is a side elevation of the interlocking disks in the relation corresponding to the position of the signal and switch illustrated in Fig. 3. Fig. 10 is a plan view of the interlocking mechanism in the relation shown in side elevation in Fig. 8. Fig. 11 is a plan view of the interlocking mechanism in the relation shown in side elevation in Fig. 7. Fig. 12 is a plan view of the interlocking mechanism in the relation shown in side elevation in Fig. 9. Fig. 13 is a diagrammatic view of a modification of the invention, in which a switch is locked in closed position by mechanism independent of the switch-throwing mechanism. Fig. 14 is a diagrammatic view of the mechanism illustrated in Fig. 13 with the closed switch unlocked. Fig. 15 is a diagrammatic view of the mechanism shown in Fig. 14 with the switch thrown to the open position and unlocked. Fig. 16 is a view showing the relation of the disks for locking the switch in the closed position, as shown in Fig. 13. Fig. 17 is a view of the disks in the unlocked position for permitting the switch to be thrown, as shown in Fig. 14. Fig. 18 is a view of the position of the disks after the switch has been thrown, as shown in Fig. 15. Fig. 19 is a view of the disks in their relation for locking the switch in the open position. Fig. 20 is a plan view of a further modification of the invention for unlocking, shifting, and locking the switch by a single lever, the parts being shown as locking the switch in closed position. Fig. 21 is a plan view showing the second position of the mechanism illustrated in Fig. 20 with the locking-disk thrown to position permitting the switch to be opened. Fig. 22 is a plan view showing the third position of the mechanism illustrated in Fig. 20 in the position occupied when the switch has been opened, and Fig. 23 is a plan view showing the fourth position of the mech-

ism illustrated in Fig. 20 in the position occupied when the switch has been locked in the open position.

Referring to Figs. 1 to 12, inclusive, of the drawings, there is shown the main track 1, having a switch 2 therein, the approach to which is guarded by the distant signal 3. The switch 2 and signal 3 are so connected by the interlocking mechanism 4 that the switch cannot be opened until the signal is set at "danger," in which position it is locked by the operation of throwing the switch to the open position. This is accomplished by providing a pair of disks 5 and 6, which are fixed on the respective axles 7 and 8, journaled as in the casing 9. These disks have the respective notches 10 and 11 formed therein and are placed so that when the two notches are brought together in exact registration either disk may be turned to lock the other, the distance between the centers of the disks being less than the sum of their radii and the notch of each being formed to fit the periphery of the other. The axle 7 has a lever 12 fixed thereto, which is connected to usual mechanism 13 for operating the switch 2, so that when the lever is turned the switch is thrown and the disk 5 is revolved. The axle 8 has a lever 14 fixed thereto, which is connected to the mechanism 15 for operating the signal 3, the revolution of the lever operating the signal and simultaneously revolving the disk 6. When the switch is closed or set for the main track and the signal is down or at "safety," as shown in Fig. 1, the interlocking mechanism is in the position illustrated in Figs. 7 and 11, the switch-disk 5, and therethrough the switch 2, being locked by the signal-disk 6, the signal-disk on being turned to move the signal to "safety" having engaged the notch of the switch-disk. It will be seen that the signal-disk, and consequently the signal, cannot be moved to "safety" from the danger position unless the switch is fully closed and the disks and their connections in the position shown in Figs. 8 and 10, in which position the slightest movement of the signal locks the switch. When it is desired to open the switch, before this can be done the signal-disk 6 must be turned to the position illustrated in Figs. 8 and 10, which moves the signal to the danger position, as illustrated in Fig. 2; when the mechanism may be turned to the position shown in Figs. 9 and 12. The slightest revolution of the disk 5 to open the switch locks the signal-disk at "danger," where it is held while the switch is open by the engagement of the disk 5 with the notch 11. If desired, a movable segmental block 16, fitting the space formed by bringing together the two notches, as shown in Fig. 4, may be employed for the purpose of holding the locked disk in a fixed position at all times during the revolution of the locking-disk if turned in the opposite direction from that described.

In the modification illustrated by Figs. 13 to 19, inclusive, in which separate mechan-

isms are employed for throwing and locking the switch, the throwing operation is performed by means of a lever 17, connected by the usual pipe-line 18 with the switch 19, and the locking is effected by operating a lever 20, connected with the switch by the rods 21 and 22 and the disks 23 and 24. The rod 21 connects the lever 20 with a crank-pin 25 on the disk 23, which revolves about the center 26, and the rod 22 connects the switch 19 with a crank-pin 27 on the disk 24, which revolves about the center 28. The disk 23 has a notch 29 formed therein, adapted to fit the periphery of the disk 24, while the disk 24 has two notches 30 and 31 formed therein, each adapted to fit the periphery of the disk 23. When the switch is locked in the closed position, as illustrated in Fig. 13, the locking-disks occupy the relation illustrated in Fig. 16, the periphery of the disk 23 engaging the notch 30 of the disk 24. The switch cannot now be opened by operating the lever 17 until the locking-lever 20 has been thrown to the position illustrated in Fig. 14, by which the disk 23, connected therewith, is turned to the position shown in Fig. 17. As the notches 29 and 30 are now in exact registration, the lever 17 can be thrown and the switch opened, as illustrated in Fig. 15, the full throw of the switch moving the disk 24 to the position illustrated in Fig. 18. The notches 29 and 31 are now in exact registration, and the disk 23 may be turned to the locking position illustrated in Fig. 19 by operating the lever 20, it being impossible to move the lock unless the switch is fully thrown.

In the modification illustrated in Figs. 20 to 23, inclusive, in which the switch is thrown and locked by a single operation, the switch 32 is operated by a rod 33, having an eccentric connection with the revolute disk 34, which is provided with a notch 35, adapted to fit the periphery of a revolute disk 36. The disk 36 has a notch 37 thereon, adapted to fit the periphery of the disk 34, and is connected with the disk 34 by a lever 38, the lever being pivoted at 39 to the disk 34 and having a slotted connection 40 with a pin 41 in the disk 36. The lever 38 may be operated directly or indirectly through the connecting-rod 42 and the lever 43. With the mechanism in the position illustrated in Fig. 20 the switch is locked in closed position by the engagement of the notch 35 of the disk 34 with the periphery of the disk 36. To throw the switch, the movement of the lever 43 first turns the lever 38 about the point 39 as a fulcrum until the disk 36 has been turned to the position illustrated in Fig. 21, when it can go no farther, by reason of its engagement with the periphery of the disk 34. The point 41 now becomes the fulcrum, and the further movement of the levers turns the disk 34 and throws the switch to the position illustrated in Fig. 22. The switch is then locked in this position by the further movement of the levers, when the point 39

again becomes the fulcrum and the disk 36 is turned to the locked position illustrated in Fig. 23.

Having described our invention, we claim—

1. In a device of the character described, the combination of two revoluble plain disks having substantially parallel axes, each of said disks having a peripheral notch adapted for receiving and engaging the other of said disks, the engagement of one of said notches locking its disk against motion in either direction, a switch connected to one of said disks, mechanism for moving said switch and the disk connected therewith, and mechanism for moving the other of said disks for the purpose set forth, substantially as specified.
2. In a device of the character described, a switch, a revoluble notched plain disk connected to and movable with said switch, a second revoluble notched plain disk adapted to be engaged by said first disk and held thereby against movement in either direction, said disks having their axes substantially parallel, and mechanism connected with said second disk for indicating at a distant point the position of said switch, substantially as specified.
3. In a device of the character described, a switch, a revoluble notched plain disk connected to and movable with said switch, a second plain disk notched to permit said first

disk to turn therein and adapted for locking said first disk and switch, said first disk being notched so that said switch is locked in both closed and open positions, substantially as specified.

4. In a device of the character described, a switch, a revoluble disk connected to and movable therewith, a second revoluble disk having a peripheral notch within which said first disk is adapted to revolve, said first disk being notched to permit its engagement and locking by said second disk in two distinct positions of said switch, substantially as specified.

45 5. In a device of the character described, a switch, a revoluble notched disk connected to and movable therewith, a second revoluble notched disk, a distant lever connected with said second disk, said first disk being notched to permit its engagement and locking by said second disk in two distinct positions of said switch, substantially as specified.

In witness whereof we have hereunto set our hands, in the presence of the subscribing witnesses, this 17th day of November, 1900.

MORTON L. BYERS.
THEODORE SHAFFER.
